UNITED STATES PATENT OFFICE

HENRY ROBINSON, OF NEW YORK, N. Y.

AGITATING, ETC., MACHINE

Application filed August 21, 1929. Serial No. 387,472.

My invention relates specifically to the class of machinery in which a mass, at least several layers deep, of various substances, are enclosed in a container for agitation by 5 mechanical means, for either the thorough mixing of substances such as glucose and proteins, for the removal of dirt by washing and agitation from fruits and leafy vegetables or for uniformly abrading the jackets 10 or skins of tuber vegetables. The invention resides in the improved mechanical means for more efficiently accomplishing the ends mentioned with less waste of material in abrading, with greater compactness, economy 15 of space and in less time.

The improved mechanism I employ to accomplish the stated purposes or objects, produces sufficient centrifugal and centripetal motion upon the entire mass of material to 20 be mechanically worked on in the container of the machine, either for mixing, washing or abrading in a satisfactory manner in the most circumscribed space and in the least time, and which container has a door adapted 25 to be opened so that the contents will be immediately, completely and automatically ejected by centrifugal force to an outside receptacle, and on the closing of which door, the container will be ready for another operation.

In connection with my prior inventions, as exemplified in United States Patents Number 809,582 issued January 9, 1906, and 942, 35 932 issued December 14, 1909, in particular, I aimed to accomplish with the means disclosed therein, the same stated purposes and objectives as in this present invention, but only succeeded to the relatively limited extent of producing a practically satisfactory 40 commercial machine for paring tuber vegetables by the use of a revolving disk with raised or scoop-shaped humps thereon that produce at a comparatively high speed of operation, sufficient centrifugal and centripetal 45 force as to impart the necessary motion to such compact solid bodies to effect substantially uniform abrasive action and avoid such gravity pressure or weight on the superposed layers of the vegetables in the container as arrests and checks the forces and

movements, to a more or less extent which in that construction results in excessive friction and waste on the lowermost or bottom layers of the vegetables, especially those which are caught in the apex of the angle forming the 55 circumference or periphery of the revolving bottom disk and the contiguous upright inner sides of the containing cylinder and which are ground to various degrees of flatness, if not entirely ground and wasted especially in 60 the case of smaller ones. This oft occurring condition is commonly termed "overloading" the machine due to the ignorance or carelessness of the operator and it results in a considerable loss or waste of vegetables. 65

As to the second object of my present invention, in the washing and cleaning of adhering dirt from fruits and leafy vegetables, especially spinach, cabbage, kale and the like, 70 my previous mechanical contrivances as illustrated in the aforesaid patents, were entirely inoperative when the containing cylinder was filled or even half filled therewith, because the revolving bottom disk with the humps, did not impart any motion or agitation 75 for the uniform cleaning and washing of the same.

While, as stated, the general aims or objects of my present invention are identical with those in my prior inventions of the 80 patents aforesaid, the present mechanical means I employ to accomplish the same, are entirely and radically different and of such improved construction as to be positive in action whether operating on solid or compact 85 material such as fruit, tuber vegetables or leafy vegetables, to always impart the same uniform movement of agitation and on the conclusion of the operation, effect complete ejection of the mass from the container, irrespective of the depth, bulk or weight of the material worked on, at highest efficiency and with a minimum waste of material, space and time.

I have also found in connection with the 95 present invention, that by substituting a solid instead of a perforated disk or plate, the same simple mechanism produces desirable and satisfactory results in the thorough mixing of liquid, semi-liquid, and doughy sub- 100

stances of various densities, and in addition, the present apparatus ejects or discharges the material automatically from the machine into an outside receptacle as contrasted with laborious hand removal of the contents from the containers of mixing and kneading machines at present in use.

Having thus stated the objects or aims of the present invention, I will now proceed to describe, in detail, by way of example, constructions which may carry the same into effect, and also describe the operation thereof.

In accompanying drawings illustrating the invention:

15 Figure 1 is a view of a preferred form, half in front elevation and half in central vertical section;

Figure 1^a is a section taken on line 1^a—1^a of Figure 1;

20 Figure 2 is an inverted plan view of the stationary disk or tray;

Figure 3 is a fragmentary top view of the upper edge portion of the base or bowl;

25 Figure 4 is a plan view of one form of agitating or abrading element;

Figures 5 and 6, respectively, are detail cross sectional views taken on the lines 5—5 and 6—6 of Figure 4;

30 Figure 7 is an edge view of the agitating element of Figure 4 looking toward the same from the lower edge of Figure 4;

Figure 8 is a plan view of a modified form of agitator or abrader;

35 Figures 9 and 10, respectively, are cross sectional details taken on the lines 9—9 and 10—10 of Figure 8;

Figure 11 is a plan view of another modified form of abrader or agitator;

40 Figure 12 is a cross sectional view taken on the line 12—12 of Figure 11;

Figure 13 is a plan view of the agitator as shown in Figure 4, suggesting its use without an abradant surface;

45 Figure 14 is a detail vertical sectional view through the device when used primarily as a mixing or kneading machine; and

Figure 15 is a plan view of a further modified form of agitator.

Referring specifically to the drawings, 50 wherein like reference characters designate like or corresponding parts, one preferred construction is illustrated in Figures 1 to 7, the complete assembly being shown, primarily, in Figure 1. In such construction, 10 55 designates a base or bowl which is preferably made in a single metallic casting and has an upstanding marginal wall 11 and a central hollow bearing 12 terminating below the upper edge of said wall. Legs 13 may support 60 the bowl.

At suitable intervals, the wall 11 along its inner surface, and below the top, has integral open socket members 14 whose cavities are designated 15 (Figures 1 and 3). A cylinder 65 or chamber member 16 removably surmounts

the wall 11 and is also preferably a single metallic casting. The cylinder 16 forms a chamber to accommodate vegetables or the various other materials which may be agitated and washed, or agitated, pared and washed, or mixed or kneaded, according to the specific purposes for which the machine is constructed. In the preferred form of the machine, the interior surface of the cylinder throughout, as at A, is rendered rough or abradant as by permanently applying carbocundum or the like thereto. Said cylinder 16 may be thickened at its lower edge so as to provide a shoulder 17 which rests on the wall 11, an annular depending flange 18 inwardly thereof and telescoping into bowl 10, and a shoulder 19 in line with shoulder 17 on the opposite side of flange 18. A removable cover 20 rests on cylinder 16 while a discharge opening and conventional closure door are provided for the cylinder at 21.

A vertical operating shaft or spindle 22 is journaled in bearing 12 (otherwise mounted and driven as hereinafter described) which extends above said bearing 12, through an opening in a stationary foraminous or solid disk or tray 23, and into a hub 24 of an agitating element 25 which also serves as the paring member in the present type of machine, and the construction of which member or element 25 forms a basic part of my invention. A set-screw 26 is one means whereby the element 25 may be secured to the shaft 22.

Said disk or tray 23 is removable and is 100 of a diameter in the present type of machine, where it is marginally spaced from the inner wall of the chamber as shown in Figure 1 so that the water and washings may overflow the same. In some instances, however, as hereinafter disclosed, said disk or tray 23 may be solid and of the same diameter as the internal diameter of the bowl 10. In order to mount the disk or tray 23 against rotation, integral lugs 27 (Figures 1 and 2) extend therefrom and into the cavities 15. Said disk or tray 23 rests on a shoulder 12' on the bearing 12 and a reduced portion 28 on said bearing 12 extends through and above the disk 23 into hub 24 to exclude water and dirt 115 from the bearing. The parer or agitator is slightly spaced above the adjacent surfaces of the disk or tray.

As shown in Figures 1 to 7, the agitator 25 may be a single metallic casting and comprise a plate portion 30 and a centripetal impulsive relatively attenuated projection 31, the former extending, for instance, approximately 90° about the center of the parer or agitator.

Plate 30, at one portion thereof, is higher than the remainder and at the zone indicated at B, has an abradant surface similar to the previously mentioned surface A of the cylinder. Such highest portion may be a ridge 125

32 radiating from the center of the agitator or parer 25 and the plate may gradually slope or curve downwardly from the ridge 32 to the side edges of the plate. Through the rotation of the agitator or parer, it imparts centrifugal action to the vegetables or materials to throw them against the inner surface of the cylinder to pare them when such surface as A is employed. The upper surface 5 of the disk 23, as shown at C, may also be abradant similarly to surfaces A and B. The surfaces A and C coact to pare the vegetables and the surface B while necessary in my previously mentioned patents, is not essential 10 in the herein described invention, although such feature may be optionally employed. The vegetables falling from such inner surface of the cylinder, are caught or engaged by the centripetally impulsive projection 15 31 which is generally hook-shaped and extends downwardly and forwardly in the direction of rotation, such direction being indicated by the arrow in Figure 4.

The highest point of projection 31 is 20 higher than the ridge 32 and the upper edge of such projection extends downwardly from the highest point toward the center of the agitator or parer whereby the projection is relatively thin or lower than its proximal and 25 distal ends as at 33. Said portion 33 is relatively narrow so as not to interfere with the turning or agitation of the material engaged thereby. As a result, when the vegetables are 30 engaged by projection 31, they are given a positive mechanical centripetal impulse or motion which causes them to travel from said projection across portion 33 into disk 23 from 35 which they are scooped up by the plate 30. As a result of continuous rotation of the parer 40 or abrader for a predetermined length of time, a mass of potatoes, other vegetables or materials within the cylinder, are constantly moved downwardly, by gravity, centrifugally, centripetally and upwardly, the elements of the mass constantly interplaying 45 through mechanical force and the skins being removed by attrition or pecking action of the abrading surfaces A and C, alone, or aided by surface B, if employed.

50 Simultaneously with the operation of the agitator, water continuously flows from any desired source through a nozzle 34 under control of a valve 35 into cylinder 16, thus constantly cleansing or flushing the potatoes or 55 materials so that the removed skins will be flushed by the water over the edge of the disk or tray 23 and when the tray is perforated, as in Figure 1, also drawn by the water through the perforations thereof, into the bowl 10 and discharged from the latter as through a 60 waste pipe 36 coupled thereto.

After such operation, the door 17 is opened, as a result of which, the agitator or parer 25 discharges the potatoes or materials through 65 the doorway controlled by said door, through

centrifugal force, appropriate means being provided to catch or receive the potatoes or materials.

While any suitable means may be used to drive the operating shaft or spindle 22, I 70 have shown and will now describe one form thereof, by way of example. A housing 36 is bolted at 37 to the under surface of bowl 10 which has a socket bearing 38 journaling the lower end of said shaft 22. Between the 75 bearings 12 and 38, a worm wheel 39 is keyed to shaft 22, the same abutting the former bearing and resting on a ball bearing device 40 supported on the bearing 38. A horizontal shaft 41 is journaled in bearings 42 on housing 36 and has a worm 43 keyed thereon which meshes with wheel 39. An L-shaped bearing 44 is fastened to bowl 10 and journals shaft 41 and an inclined upstanding shaft 42 which drives the former through the medium 80 of intermeshing bevel gear wheels 45 and 46. A bevel gear wheel 47 is keyed to the top of shaft 42 and meshes with a bevel gear 48 on the main shaft 49 of an electric motor 50. Said motor 50 may be mounted on a flange 51 85 of a bearing 52 surrounding a post or rod 56 having a pedestal 53 to rest on or be secured to the floor or same support as the legs 13, and which may also be fastened by a bracket 54 to bowl 10. On bracket 51, a bearing 55 90 is provided for shaft 42. An arm 57 is integral with bearing 52 and is clamped by a bolt 58 to an arm 59 integral with cylinder 16. Such structure thus holds the cylinder 16 immovably in place as well as forms a bearing 95 for the motor support 52, preventing vibration.

A modified form of the agitator 25 is disclosed in Figures 8, 9 and 10, the same differing from the previous form only with respect 105 to a raised portion or ridge 32' which is provided on a plate portion 30' equivalent to that at 30. The rib 32' instead of extending diametrically, extends from one end of the plate and curves inwardly on a line between 110 the periphery and center of the disk.

The plates 30 and 30' in the forms of agitators described, respectively, optionally have upwardly extending marginal flanges 30^a and 30^b.

Another modified form of agitator or similar member to be used, if desired, in place of those at 25 and 25', is shown at 25'' in Figures 11 and 12, the same differing therefrom with respect to the plate portion which is designated 30^a having one edge 32^a higher than the other edge, so that the plate will function like those at 30 and 30' with the raised edge 32^a functioning as a ridge. It 120 will be noted that this form of the invention does not employ a flange equivalent to 30^a or 30^b of the previous forms.

As before set forth, the agitator or equivalent members such as 25, 25' and 25'' may have their surfaces entirely smooth and thus 130

devoid of abradant material as when the type of machine employed is for the purpose of washing leafy vegetables, or mixing of kneading substances or materials, and an example of such a smooth agitating member is given in Figure 13, the same reference characters as in the form of Figures 1 to 7 being used, since merely the abrading surface or surfaces, and their corresponding function, are omitted.

Also in cases where the machine is built to mix or knead materials, water is not continuously supplied to the chamber or cylinder of the machine, although the same may be periodically added or supplied, if desired, all parts of the machine are devoid of abradant material. This feature is exemplified in Figure 14. In this form of mixer or kneader, the disk or tray is imperforate and there is no leakage around its periphery because the disk or tray is of greater diameter than in the previous forms and is overlapped by a shoulder 19' on the cylinder. Otherwise, the same reference characters as applied in the form of Figures 1 to 7, have been used.

In Figure 15, another modified form of agitator or the like is shown, differing from the previous forms in that it employs a plurality of centripetally acting impulse projections at 60 and 61, branching from the same shank 62 which is formed integrally with a plate 63. The projections 60 and 61 are identical in construction with those at 31 and the plate 63 is identical with that at 30 and it may optionally employ or be devoid of abradant material applied as at B in Figure 4. Such an agitator or similar means as shown in Figure 15 is useful where the machine may have an intermittent rotating action or may be adapted, at times, to rotate in opposite directions. The upper edges of projections 60 and 61 are connected by an integral web 64 which prevents material from falling between them.

Since the forms illustrated and described are simply examples of the application and practice of my invention, it is to be understood that various additional changes may be resorted to within the spirit and scope as defined by appended claims.

I claim as my invention:

1. A machine of the class described having a centripetally impulsive agitating means having an arm-like projection on one side of its axis, said projection extending generally radially and laterally, said projection being laterally dished and adjacent its outer end having a portion higher than the part thereof between the same and said axis, said part being relatively narrow whereby it does not affect the motion of material during agitation, substantially as described.

2. A machine of the class described having a centripetally impulsive agitating means having a curved arm-like projection on one

side of its axis, said projection extending generally radially and laterally, said projection being laterally dished and adjacent its outer end having a portion higher than the part thereof between the same and said axis, said part being relatively narrow whereby it does not affect the motion of material during agitation, substantially as described.

3. A machine of the class described having a centripetally impulsive agitating means having a curved arm-like projection on one side of its axis, said projection slanting downwardly and forwardly at the material-engaging surface, the slant of said surface increasing in abruptness from the free end toward the axis of said means, and said projection adjacent its outer end having a portion higher than the part between said portion and said axis, said part being relatively narrow whereby it does not affect the motion of material during agitation.

4. A machine of the class described having a centripetally impulsive agitating means having an arm-like projection on one side of its axis, said projection adjacent its outer end having a portion higher than the part thereof between the same and said axis, said part being relatively narrow whereby it does not affect the motion of material during agitation, and a segmental extension on the opposite side of said axis spaced at its sides from said projection, substantially as described.

5. A machine of the class described having a centripetally impulsive agitating means having an arm-like projection on one side of its axis, said projection extending generally radially and laterally, and being laterally dished and adjacent its outer end having a portion higher than the part thereof between the same and said axis, said part being relatively narrow whereby it does not affect the motion of material during agitation, a segmental extension spaced at its sides from said projection and being disposed on the opposite side of said axis having a portion between the periphery and axis higher than the remainder thereof, substantially as described.

6. A machine of the class described having a centripetally impulsive agitating means having an arm-like projection on one side of its axis, a hub integral with said projection, said projection adjacent its outer end having a portion higher than the part thereof between the same and said axis, said projection extending generally radially and laterally and having its forward surface slanting downwardly and forwardly, said part being relatively narrow whereby it does not affect the motion of material during agitation, a segmental extension on the opposite side of said axis integral with said hub and having a portion between the periphery and axis higher than the remainder thereof, said projection and extension being of the same radial

extent from said axis, substantially as described.

7. A machine of the class described having a cylinder provided with a lateral discharge opening, rotatable means in said cylinder adjacent the base thereof, a centripetally impulsive agitating device carried by said means, and a centrifugally impulsive agitating device spaced at its sides from the first mentioned device and carried by said means and located on a different side of the axis of said means from the first mentioned device, both of said devices having the same radial extent from said axis, and means beneath and relatively close to the first mentioned means to support material between said devices during agitation, substantially as described.

8. A machine of the class described having rotatable means, a centripetally impulsive agitating device carried by said means, and a centrifugally impulsive agitating device spaced at its sides from the first mentioned device and carried by said means and located on a different side of the axis of said means from the first mentioned device, and means beneath and relatively close to the first mentioned means to support material between said devices during agitation, the centrifugally operating device having a portion higher than the remainder thereof located between its periphery and axis, said remainder being relatively narrow whereby it does not affect the motion of material during agitation, substantially as described.

9. A machine of the class described having means providing a chamber with a lateral discharge opening, a rotatable device therein adjacent the base thereof for engagement with the contents, said device having an extension on one side of its axis to centrifugally engage the contents, and an arm-like extension on the other side of the axis to centripetally engage said contents, said device and extension being of substantially the same radial extent, and means relatively close to the first mentioned means to support said contents in the spaces between the first extension and the arm-like extension, substantially as described.

10. A machine of the class described having means providing an agitating chamber provided with a lateral discharge opening, a relatively stationary disk therein adjacent the base thereof to support material during agitation, and an agitator device of skeleton form in said chamber above the disk to centrifugally and centripetally move the contents and discharge the same when said opening is exposed, substantially as described.

11. A machine of the class described having a chamber means provided with a lateral discharge opening, a relatively stationary disk removably mounted therein adjacent the base, a rotatable shaft extending above said

disk, and an agitator device carried by said shaft above and relatively close to said disk to centrifugally and centripetally move the contents and discharge the same when said opening is exposed, substantially as described.

12. A machine of the class described having a chamber means provided with a lateral discharge opening, having an upstanding bearing, a non-rotatable disk resting on said bearing to support material during agitation, a shaft journaled in said bearing and extending above the same and adjacent portion of said disk, an agitator carried by the shaft above and relatively close to said element comprising a substantially segmental extension to centrifugally move material, and an arm-like extension spaced at its sides from said first extension to centripetally move material, said arm-like extension extending generally radially and laterally and being laterally dished and having a relatively low portion inwardly of its free end, said low portion being relatively narrow whereby it does not affect the motion of material during agitation, substantially as described.

13. A machine of the class described having a base having sockets on the interior thereof below its upper edge, a bearing on the base terminating short of the top thereof, a disk member to support material being agitated, said disk member resting on said bearing and having lugs engaging said sockets, a cylinder resting on the upper edge of said base having a portion telescoping with said base, an agitating member operating above and relatively close to the disk, and an operating shaft for said agitating member journaled in said bearing and extending through the disk, substantially as described.

14. A machine of the class described having a chamber provided with a lateral discharge opening, a rotatable device therein adjacent the base thereof for engagement with the contents, said device having an extension on one side of its axis to centrifugally engage the contents, and an arm-like extension on the other side of the axis to centripetally engage said contents, and means relatively close to the first mentioned means to support said contents in the spaces between the first extension and the arm-like extension, the last mentioned means being elevated with respect to the base of the chamber and in draining relation to the chamber.

15. The subject matter of claim 14 wherein the arm-like extension extends generally radially and is laterally dished, said projection having a part relatively narrow and low between its outer end and said axis so as not to affect the motion of material during agitation.

16. A machine of the class described having a chamber provided with a lateral discharge opening, a rotatable device therein

adjacent the base thereof for engagement with the contents, said device having an extension on one side of its axis to centrifugally engage the contents, an arm-like extension on the other side of the axis to centripetally engage said contents, said extension extending generally radially and laterally and being laterally dished, said extension having a part relatively narrow and low between its outer end and said axis so as not to affect the motion of material during agitation, and perforated means relatively close to the first mentioned means to also support the contents.

17. The subject matter of claim 16 wherein the projection is similarly shaped on opposite sides of a radial line so that the agitating means may be operated in either direction.

In testimony whereof I have affixed my signature.
